UNITED STATES PATENT OFFICE.

ANTON HORVAT, OF BALTIMORE, MARYLAND.

DESIGN FOR A WEDDING RING.

Application filed July 31, 1926. Serial No. 18,559. Term of patent 14 years.

To all whom it may concern:

Be it known that I, ANTON HORVAT, a citizen of the United States, residing at Baltimore, in the county of Baltimore and State of Maryland, have invented a new, original, and ornamental Design for Wedding Ring, of which the following is a specification, reference being had to the accompanying drawing, forming part thereof.

Figure 1 is a perspective view of the ring,

Figure 2 is a detail view of the outer design,

Figure 3 is a detail view of the inner design.

Figure 4 is a detail view of the edge design.

I claim:

The ornamental design for a wedding ring, as shown.

ANTON HORVAT.
